UNITED STATES PATENT OFFICE.

ADRIAN D. ADRIANCE, OF NEW YORK, N. Y.

CLUTCH.

1,034,183.

Specification of Letters Patent. Patented July 30, 1912.

Application filed October 17, 1911. Serial No. 655,132.

To all whom it may concern:

Be it known that I, ADRIAN D. ADRIANCE, a citizen of the United States, residing at New York city, in the county of New York 5 and State of New York, have invented certain new and useful Improvements in Clutches, of which the following is a specification.

This invention relates to hoisting and similar mechanisms, and it has reference particularly to hoisting apparatus of the kind wherein the hoisting operation is automatically arrested after having proceeded to a predetermined extent.

According to my invention the driven member of a clutch having its members, driving and driven, side by side has a terminating or non-continuous cam way facing away from the driving clutch member, 15 and means is employed which, engaging said cam way, presses said clutch members together to cause their engagement, ceasing to maintain their engaging relation with each other when the driven clutch member in its 20 rotation has carried its cam way out of the range of the pressing means. The driven clutch member being normally induced to rotate backward under the pull of the load in the present adaptation said cam way at 25 its terminus is adjoined by a surface extending toward the driving member to form a stop with which the pressing means engages when the cam way has cleared the same with the effect of locking the driven 30 clutch member against re-rotation under the pull of the load; and preferably in this 35 adaptation a checking shoulder is also formed on the driven clutch member, such shoulder being so disposed as to engage the 40 pressing means substantially at the moment when it is cleared by the cam way and arrest the driven clutch member precisely at a predetermined point in its rotation. Further, the cam way is formed so as to present to 45 the pressing means a rise progressing in the direction of re-rotation of the driven clutch member, whereby the pressing means may be utilized to ease the backward rotation of the driven clutch member under the pull of 50 the load. Again, means is provided for limiting the action of the pressure applying means upon the cam-way having cleared the same.

I have illustrated my invention in the accompanying drawings in connection with a farm machine forming the subjects of other

applications filed by me, said drawings showing, Figure 1, a side elevation of the said machine, provided with the improved hoisting mechanism; Fig. 2 a plan view of what is shown in Fig. 1; Fig. 3 a plan view showing the hoisting mechanism on a larger scale, a certain part being removed; Fig. 4 an inside face view of one of the driving clutch members; Fig. 5 a sectional view on the line $x-x$ of Fig. 4; Fig. 6 an outside face view of the complementary clutch member; Figs. 7 and 8 elevations of the clutch member shown in Fig. 6 looking toward the periphery thereof from different points; Fig. 9 a plan view of the foot lever; Fig. 10 a fragment of one of the clutch controlling levers; and, Fig. 11 is a detail view illustrating the connection between one of the controlling levers and a T-link connecting said lever with the operating lever.

In the drawings *a* designates a traction engine, and *b* a harrow attachment pivotally supported on the rotary shaft *c* and constituting the "load" which at times it is necessary to elevate and then lower gradually and without undue shock.

d designates two driving clutch members secured on the inner ends of the hubs *e* of gears *f* which are journaled in hangers *g* and mesh with pinions *h* on the shaft *c* connected by a transmission mechanism *i* with a suitably driven driving shaft *j*. It is assumed that the parts *d* to *j* are normally in rotation.

On the hub *e* of each gear is a driven clutch member *k* freely revoluble thereon, *l* being a collar fixed on the hub and retaining the driven clutch member in place. The clutch member *k* is normally held out of clutching engagement with the clutch member *d* by the spring pressed plugs *m* arranged in one of said members and bearing against the other; the clutch shown is of the friction type, the friction grip being afforded by wood, fiber, cork or other suitable friction grip devices *n* set in the face of one clutch member in position to impinge against the adjoining face of the other.

The clutch members *k* are preferably grooved, as at *o*, for the reception of the cables *p* or other flexible connections wound thereon and attached at their free ends to the "load," being in the present instance passed over the pulleys *q*. It will be observed that upon pressure being applied to force the clutch members *k* apart, that is,

each against its complementary clutch member d , the clutch members k will be rotated by the clutch members d , the cables wound up on the drums afforded by the clutch members k and the load raised. The movement of the clutch members k into clutching engagement with the clutch members d is effected from a foot treadle r forming an operating lever and fulcrumed on a shaft s through the medium of a T-link t pivotally connected with the foot lever and having the cross arms t' thereof passed freely through studs u swiveled in the long arms v' of the controlling levers v fulcrumed in brackets w secured on the frame of the traction engine and having their short arms v^2 provided with rollers v^3 to engage said clutch members k in the manner now to be described.

Each clutch member k on the surface thereof facing away from the clutch member d has a terminating or non-continuous concentric cam-way x (i. e., a cam-way which extends but part way around the axis of rotation of said clutch member) adjoined at its terminus by a surface y extending toward the driving clutch member to form a stop, said surface being in the adaptation shown one side of a recess z . The other side of said recess z merges into a shoulder 2 forming one face of a projection 3 on the clutch member, the disposition of said shoulder being such that in the rotation of the clutch member it will engage the roller v^3 so that the latter will positively stop the rotation of the clutch member. The clutch member k under the impulse of clutch member d rotates in the direction of the arrows shown in the drawings, and the cam way x is a cam surface whose rise progresses reversely to the above indicated direction of rotation of the clutch member k (Figs. 3 and 8).

In operation, the clutch members d being in rotation, upon pressure being applied to the foot treadle r sufficient to cause levers v to press the clutch members k into clutching engagement with clutch members d , the former will be rotated, winding the cables thereon and therefore raising the load. This will continue until the rollers v^3 reach the recesses z of the clutch members k when the rotary motion of the clutch members k will cease, the shoulders 2 of said clutch members having been brought up against the rollers v^3 of the levers v . At this time, it is desirable to provide means for limiting the pressing action of the pressure means, including the levers v , so that the operator will not inadvertently continue the clutch members in clutch engagement with each other: Hence each bracket w is formed at 4 with a stop which the short arm v^2 of the adjoining lever impinges against, preventing its exerting further pressure on mem-

ber k calculated to reestablish its clutching engagement with clutch member d . When it is desired, now, to allow the load to lower, the pressure on the foot treadle is relaxed until the rollers v^3 clear the recesses v , the load of course at this time tending to rotate the clutch members k backward. By now removing the pressure from the treadle gradually the operator may "ease" the fall of the load, having in this the assistance of the rise of the cam surfaces afforded by the cam way x of each clutch member k , against which the roller v^3 is bearing, and the co-acting resistance afforded by the clutch member d with which at this time the clutch member k is of course held in wiping contact.

By employing the anti-friction bearing, such as rollers v^3 , as its contact part, the release of the clutch member k from the position in which it is held by the lever when it engages the stop y is accomplished without binding and instantly upon relaxation of the pressure.

Having thus fully described my invention, what I claim as new and desire to secure by Letters Patent is:—

1. A hoisting mechanism comprising rotary driving and driven clutch members arranged side by side, and means, exerting pressure from opposite sides of and upon said members and relatively to which said members are rotary, for forcing said members into clutching engagement with each other, the part of the surface of the driven clutch member receiving the impact of said means being a terminating cam-way extending around the axis of rotation of said member, substantially as described.

2. A hoisting mechanism comprising rotary driving and driven clutch members arranged side by side, and means, exerting pressure from opposite sides of and upon said members and relatively to which said members are rotary, for forcing said members into clutching engagement with each other, the part of the surface of the driven clutch member receiving the impact of said means being a terminating cam-way extending around the axis of rotation of said member, and being adjoined at its terminus by a surface extending toward the driving clutch member and thereby forming a stop for engagement by said means to restrain the driven clutch member against re-rotation, substantially as described.

3. A hoisting mechanism comprising rotary driving and driven clutch members arranged side by side, and means, exerting pressure from opposite sides of and upon said members and relatively to which said members are rotary, for forcing said members into clutching engagement with each other, the part of the surface of the driven clutch member receiving the impact of said

means being a terminating cam-way extending around the axis of rotation of said member, said driven clutch member having a checking shoulder engageable with said

5 means and substantially coinciding with the terminus of the cam-way, substantially as described.

4. A hoisting mechanism comprising rotary driving and driven clutch members arranged side by side, means, exerting pressure from opposite sides of and upon said members and relatively to which said members are rotary, for forcing said members into clutching engagement with each other, 15 the part of the surface of the driven clutch member receiving the impact of said means being a terminating cam-way extending around the axis of rotation of said member, and means for limiting the pressure of the 20 first means upon said cam-way having cleared the pressure-exerting means in the rotation of the driven clutch member, substantially as described.

5. A hoisting mechanism comprising rotary driving and driven clutch members arranged side by side, means, exerting pressure from opposite sides of and upon said members and relatively to which said members are rotary, for forcing said members into clutching engagement with each other, the part of the surface of the driven clutch member receiving the impact of said means being a terminating cam-way extending 30 around the axis of rotation of said member, and being adjoined at its terminus by a surface extending toward the driving clutch member and thereby forming a stop for engagement by said means to restrain the driven clutch member against re-rotation, 35 substantially as described.

and means for limiting the pressure of the 40 first means upon the same having engaged said stop, substantially as described.

6. A hoisting mechanism comprising rotary driving and driven clutch members arranged coaxially side by side, the driven 45 clutch member having a cam-way facing away from the driving clutch member, extending around the axis of rotation and formed with a rise progressing in the direction opposite to that assumed by the driven 50 clutch member under the driving impulse of the driving clutch member, and means, engaging said cam-way, for pressing said clutch members into clutching engagement with each other, substantially as described. 55

7. A hoisting mechanism comprising rotary driving and driven clutch members arranged coaxially side by side, the driven clutch member having a terminating cam-way facing away from the driving clutch 60 member and extending around the axis of rotation and a surface extending toward the driving clutch member at the terminus of the cam-way to form a stop, and means for pressing said clutch members together into 65 clutching engagement with each other including an anti-friction bearing impinging against said cam-way and, in the rotation of the driven member, adapted to engage said stop and lock the driven member against re-rotation, substantially as described. 70

In testimony whereof I affix my signature in presence of two witnesses.
